UNITED STATES PATENT OFFICE.

HUGH HARRIS AND SAMUEL M. REESE, OF GALION, OHIO.

WAGON-RACK.

SPECIFICATION forming part of Letters Patent No. 705,755, dated July 29, 1902.

Application filed May 27, 1902. Serial No. 109,237. (No model.)

To all whom it may concern:

Be it known that we, HUGH HARRIS and SAMUEL M. REESE, citizens of the United States, residing at Galion, in the county of Crawford 5 and State of Ohio, have invented certain new and useful Improvements in Wagon-Racks; and we do hereby declare the following to be a full, clear, and exact description of the invention, such as will enable others skilled in the 10 art to which it appertains to make and use the same, reference being had to the accompanying drawings, and to the figures of reference marked thereon, which form a part of this specification.

15 Our invention relates to wagon-racks, and comprises an attachment for a wagon-box to permit of its being used as a stock and hay rack.

Our object is to provide a rack which may 20 be adjusted to any angle from the perpendicular to the horizontal.

A further object is to provide a simple, strong, and efficient device of this character.

25 Novel details in the construction and arrangement of the several parts of the invention will be apparent from the detailed description hereinafter and the appended claims, when taken in connection with the accompanying drawings, forming part hereof, 30 in which—

Figure 1 is an end elevation of a wagon box and rack, two positions of the rack being shown in full lines and a third position in dotted lines. Fig. 2 is a side elevation of a 35 part of the wagon box and rack.

Referring to the drawings, 4 denotes the side-board of a wagon-box, 5 the floor, and 6 the end-gate. The rack is indicated at 7 and comprises longitudinal bars 8, secured to a 40 bracket 9. A casing 10, provided with an opening 11 at the top and front ends thereof, has ears 12, to which the bracket 9 is pivoted. Said bracket is adapted to enter the casing through said openings. To lock the bracket in the position to which it may be adjusted, we provide openings 13 in the arm 9^a of the bracket 9. We also provide an opening 14 in the casing. By causing this opening to register with one of those in the arm 9^a and pass-

ing a spring-pin 15 through the same the 50 bracket is securely locked. Said spring-pin 15 is secured to the side of the casing 10, and by withdrawing it from the openings the bracket is released and may then be adjusted to another position. We have shown only two 55 openings 13 in the arm 9^a; but by increasing their number the number of positions to which the bracket may be adjusted will be increased also. The rear and bottom ends of the casing 10 are provided with flange 16, by which 60 it is secured, by means of bolts 17 or otherwise, to the projecting bottom cleats 18 and the side-boards 4 of the wagon-box. The bracket 9 is also provided with a flange 19, to which the longitudinal bars 8 are secured by 65 means of bolts 20 or otherwise. Said flange and the flange 16 also serve to support the bracket when in horizontal position, the flange 19 resting on the top of the casing 10, as shown in Fig. 1. The sides of the casing are corrugated, as indicated at 21, insuring greater 70 strength and stiffness of the same.

The number of brackets required depends, of course, on the length of the wagon. They may also be made in various sizes in order to 75 fit wagons of different sizes.

Having thus described our invention, what is claimed as new, and desired to be secured by Letters Patent, is—

1. The combination with a wagon-box, of a 80 rack comprising a bracket, longitudinal bars secured thereto, a housing inclosing said bracket, and means for varying the inclination of the bracket and locking it to the housing, substantially as shown and described. 85

2. The combination with a wagon-box, of a rack comprising a bracket, longitudinal bars secured thereto, a housing for said bracket, openings in the bracket and housing, and a spring-pin engaging said openings for locking the bracket to the housing, substantially 90 as shown and described.

3. A bracket comprising an adjustable arm, a housing inclosing the same to which said arm is pivoted, and means for varying the 95 inclination of said arm and locking the same to the housing, substantially as shown and described.

4. A bracket comprising an adjustable arm, a housing therefor to which said arm is pivoted, openings in said arm and housing, and a spring-pin secured to the housing adapted to engage said openings to hold the arm in adjusted positions, substantially as shown and described.

In testimony whereof we affix our signatures in presence of two witnesses.

HUGH HARRIS.
SAMUEL M. REESE.
